UNITED STATES PATENT OFFICE.

DONALD S. BARROWS, OF PATERSON, NEW JERSEY, ASSIGNOR TO AMERICAN CAR AND FOUNDRY COMPANY, OF ST. LOUIS, MISSOURI, A CORPORATION OF NEW JERSEY.

DOOR-OPERATING DEVICE.

1,042,384.

Specification of Letters Patent.

Patented Oct. 29, 1912.

Application filed July 6, 1911. Serial No. 637,201.

To all whom it may concern:

Be it known that I, DONALD S. BARROWS, residing at Paterson, Passaic county, New Jersey, and being a citizen of the United States, have invented certain new and useful Improvements in Door-Operating Devices, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a transverse sectional view of a car illustrating the invention, the section being taken on line 1—1 of Fig. 2 looking in the direction indicated by the arrow. Fig. 2 is a plan view of a fragment of a car, showing the invention applied with portions of the view shown in section taken on the line 2—2 of Fig. 3. Fig. 3 is a section taken on line 3—3 of Fig. 1. Fig. 4 is a vertical sectional view through portion of a cross bearer illustrating a slightly modified form of retaining means for a rack bar employed in the device.

The object of the invention is to provide means for opening and for closing and locking in closed position the doors of what are commonly known as "general service cars," that is cars having flat bottom portions, comprised wholly or partly of doors which are adapted to be dropped or opened to discharge the lading.

While any suitable means may be provided for operating the principal operating shaft, I have shown no means in the drawings as various devices are common in the art for that purpose.

The principal object of this invention is to provide means which will permit opening and closing the doors with a minimum power and which will provide the means for positively locking the doors in closed position.

Referring to the parts, F is the operating shaft extending substantially the length of the car, which shaft is supported in cross

bearers or diaphragms H, while doors G are connected by suitable hinges I, with the center sills B and which doors extend outwardly as shown in the drawing, to slightly beyond the side plate-girder B'. A sill cover plate S is provided where two center sills are used, though said cover plate may be omitted in case the car is constructed with a single center sill.

Connected to the operating shaft F at suitable intervals there are pinions 1 and 65 meshing with these pinions are racks 2 best shown in Fig. 1, which racks travel in engagement with rollers a held on pins b in guide plates 3 which swivel on the shaft F.

The guides 3 may comprise each a single 70 plate as illustrated in Figs. 1, 2 and 3 or they may comprise each a pair of plates disposed upon opposite sides of the pinion 1 as illustrated in the modified structure shown in Fig. 4.

Connected to the outer end of each of the racks 2 is a bell crank lever 4 which is mounted on a pivot 5, supported in a suitable bearing 6, which bearing is connected with the diaphragm. 75

The shorter arm of the bell crank 4 is connected with the rack 2 while its longer arm extends, when the door is in closed position, relatively vertically as shown in full lines in Fig. 1 and carries at its upper end a suitable 80 roller 7 adapted to bear against the lower face of the doors G, the roller 7 being carried on a laterally projecting extension of the bell crank 4 as best shown in Fig. 3.

Connected with each transverse edge of 90 the doors G is an angle guide bracket 8 against which the roller 7 bears during the operation of opening the doors.

As each edge of each of the doors G is equipped with the same locking means in 95 proximity to the transverse diaphragms of the car under frame description of one will answer for all.

Assuming the doors to be in closed position as shown by full lines in Fig. 1 and it is 100 desired to open the door, the operating shaft F is rotated in clock-wise direction carrying with it, the pinion 1 and projecting the rack 2 outwardly, that is away from the center sill, as shown by dotted lines in said Fig. 1, 105 thereby rocking the bell crank lever 4 upon its pivot, carrying the lower end of the shorter arm forward and outwardly as

shown by dotted lines in said Fig. 1, thus causing the longer arm of said bell crank lever to be thrown inwardly and downwardly in the direction indicated by the arrow in Fig. 1 to the position shown in dotted lines in said figure.

During this movement the roller 7 will bear against the angle bracket 8 which is secured to the depending flange 10 of the door and cause said door to travel to the position shown in dotted lines in said Fig. 1 to open position in which position the roller 7 will bear against the angles 10, which form the side edge portions of the door, and support the door in open position.

When it is desired to close the door the shaft F is rotated in contra-clock-wise direction, thereby carrying the rack 2 inwardly and upwardly to positions shown in full lines in said Fig. 1, rocking the bell crank lever 4 upon its pivot, causing the rollers 7 to bear against angles 10 on the door and lifting the door to its upper or closed position.

As it is necessary to lock the doors in closed position there are provided angles X near the outer ends of the angle guide brackets 8, which serve as stops to prevent excessive outward thrust of the upper angular extensions of the arms 4 of the bell crank and prevent their passage beyond the outer ends of the said brackets. These angles X are riveted to the door angles or door flanges as shown at X in Figs. 1 and 2 and serve in effect as supplemental locking means for the door lifting bell crank when the rack 2 thrusts the upper end 4 to its outermost position.

What I claim is:—

1. In a door operating device the combination comprising a door, a pivotally mounted member slidably engaging said door, an operating shaft, a pinion operated by said operating shaft, and a rack-bar engaging said pinion and being pivotally connected to said pivotally mounted member.

2. In a door operating device, the combination comprising a door, a bell crank slidably engaging said door, an operating shaft, a pinion operated by said operating shaft and a rack-bar engaging said pinion and being pivotally connected to said bell crank.

3. In a door operating device, the combination comprising a door, a pivotally mounted member, a door engaging roller carried by said pivotally mounted member, a runway formed upon said door adapted to under-lap said roller, an operating shaft, a pinion operated by said operating shaft, and a rack-bar engaging said pinion and being pivotally connected to said pivotally mounted member.

4. In a door operating device, the combination comprising a door, a pivotally mounted member slidably engaging said

door, an operating shaft, a pinion operated by said operating shaft, a rack-bar engaging said pinion and being pivotally connected to said pivotally mounted member, and a runway formed upon said door adapted to under-lap a part of said door engaging member whereby said door engaging member will force said door open.

5. In a door operating device, the combination comprising a door, a reinforcing angle fixed to said door, an angle member fixed to said reinforcing angle adapted to form a runway and means engaging in said runway for forcing said door open.

6. In a door operating device the combination comprising a door, a reinforcing angle fixed by one of its flanges to the under side of said door, a member fixed to the other flange of said reinforcing angle adapted to form a runway, and means engaging in said runway for forcing said door open.

7. In a door operating device, the combination comprising a door, a reinforcing angle fixed by one of its flanges to the under side of said door, an angle member fixed by one of its flanges to the other flange of said reinforcing angle, the remaining flange of said angle member being adapted to form, with said reinforcing angle, a runway and means engaging in said runway for operating said door.

8. In a door operating device, the combination comprising a door, a reinforcing angle fixed to said door, an angle member fixed to said reinforcing angle and means engaging a flange of said angle member adapted to force the door open.

9. In a door operating device, the combination comprising a door, a reinforcing member for said door, a member fixed to said reinforcing member adapted to form a runway, and a bell crank engaging in said runway for forcing said door open.

10. In a door operating device, the combination comprising a door, a reinforcing member for said door, a member fixed to said reinforcing member adapted to form a runway, and a bell crank projecting into said runway for forcing said door closed.

11. In a door operating device, the combination comprising a door, a pivotally mounted member slidably engaging said door, an operating shaft, a pinion operated by said operating shaft, a rack-bar engaging said pinion and being pivotally connected to said pivotally mounted member, and means pivotally carried upon said operating shaft, adapted to retain said rack-bar in mesh with said pinion.

12. In a car door operating device, the combination comprising a door, a car frame, a bell crank pivotally mounted upon said car frame, a fixed pivot for said bell crank, one arm of said bell crank engaging said door, and means engaging the opposite arm

of said bell crank adapted to swing said bell crank for closing and locking said door.

13. In a door operating device, the combination comprising a door, a lever mechanism 5 for operating said door, an operating shaft, a pinion carried by said operating shaft, a rack-bar engaging said pinion and being operatively connected with said lever mechanism, and means mounted upon said operating shaft adapted to retain said rack-bar 10 in mesh with said pinion.

14. In a door operating device, the combination comprising a door, an operating shaft, a support for said shaft, a bell crank 15 mounted on said support and slidably engaging said door and longitudinally slidably means connecting said shaft and bell crank.

15. In a door operating means, the combination comprising a door, an operating 20 shaft, supporting means therefor, and a bell

crank connected with both said shaft and said door in slidable engagement.

16. In a door operating means, the combination comprising a door, an operating shaft, supporting means therefor, a runway 25 depending from said door and a bell crank slidably engaging said runway to force the door open.

17. In a door operating means, the combination comprising a door, an operating 30 shaft, supporting means therefor, a runway depending from said door, a bell crank engaging said runway and slidably connecting means for said shaft and bell crank.

In witness whereof I have hereunto set 35 my hand in the presence of two witnesses.

DONALD S. BARROWS.
